UNITED STATES PATENT OFFICE.

HENNING NOTHDURFT, OF RICHMOND HILL, NEW YORK.

MULTIPLE FUSE.

Application filed May 2, 1924. Serial No. 710,598.

To all whom it may concern:

Be it known that I, HENNING NOTHDURFT, citizen of Germany, and resident of Richmond Hill, in the county of Queens and State of New York, have invented certain new and useful Improvements in Multiple Fuses, of which the following is a specification.

This invention relates to multiple fuses 10 in general and particularly to the kind commonly known as fuse plugs or fuse cartridges.

The prime object of my invention is to provide a multiple fuse plug which will not 15 only have the advantage of permitting the use of such a plug a number of times without necessitating the changing of the plug itself, but which has provisions for indicating that portion of the fuse which has been 20 used up.

Another object of my invention is to provide a multiple fuse plug of simple, inexpensive and electrically perfect construction adapted to be equipped for use for any current strength, depending upon the size of 25 fusible elements employed.

Another object of my invention is to provide means whereby individual contact made with each one of the fusible elements 30 is assured by broadening the contact surface, thus preventing the formation of a gap which would be detrimental to the proper working of the device.

The foregoing and further objects will 35 be more fully apparent from the following description and the accompanying drawings showing few of the preferred forms, employing my principle of construction.

Referring to the drawings, 40 Figure 1 represents a top view of my device partially broken off.

Figure 2 is a partial cross sectional view through Figure 1, taken on line 2—2.

Figure 3 is a modified form of my device.

Figure 4 is another modified form of my device.

Figure 5 is a partial top view of the modified form shown in Figure 3.

Referring to the figures, 1 and 2, numeral 50 10 denotes a solid body portion of my device which is provided with a plurality of longitudinal ducts indicated at 11 terminating at the upper ends in enlarged cavities 12.

The lower portion of the body is provided 55 with an external thread 13, which may either be of the material of the body or may

be made by pouring around the lower portion plaster of Paris or other hardening cements and imparting thereto, the desired thread shape.

Through the center of the body, there is provided a hole 14. Ducts 11 are preferably staggered and serve for receiving a fusible element indicated at 15, the lower end 16 of which is bent towards the center of the plug while the upper end 17 is broadened, and may be thus formed by pouring into the cavity 12, a small quantity of solder.

Through each duct 11, passes one fusible element and the lower ends of all the elements are shown to be connected by a conductive washer 18, while the upper ends of the elements are electrically insulated.

Above the broadened ends of the elements, there is disposed a conductive disc-shaped member 19 provided with a plurality of perforations 20 which are internally threaded so as to accommodate a threaded contacting pin 21, provided with a knob 22. Conductive member 19 has a central opening 23.

On top of the conductive member, there is provided a thin, perforable sheet 24 which may be made of white or colored paper, or thin foil and which is adapted to be pierced by pin 21, before contact may be made between the conductive member 19 and one of the heads 17 of the fusible elements 15.

The perforable sheet 24 is covered by an insulated layer or disc 25. Both of these sheets are also provided with a central hole, while the insulating member 25 has a plurality of openings 26 corresponding in number and registering with the cavities 12.

The conductive member 18 connecting the lower ends of the fusible elements is so arranged as to be clamped tight when a threaded outer shell 27 is associated with the body of the fuse.

In this way, connection is made between the outer shell and the fuse elements. An insulating washer 28 is shown to be placed centrally at the lower end of the fuse plug and against this insulating washer 28, rests another metallic washer 29, adapted to facilitate the tightening together of the different parts.

This is accomplished by inserting a bolt 30 through the opening 14 of the body, said bolt being threaded at its end indicated at 31 and engaged by a nut 32.

A similar construction is shown in Fig-

ures 3 and 5, there, however, the body portion 10' is hollow and is adapted to receive a solid filament carrier 33. This carrier is provided with longitudinal grooves 34 and 5 enlarged recesses 35; the latter dividing the broadened end of the carrier into ribs 36 as seen in Figure 5.

The grooves 34 are adapted to receive the fusible elements 15' which are bent over at 10 the lower end 16' and broadened at the upper end 17'. The broadened end rests within the recesses 35.

Again a conductive member 19', a pierceable sheet 24' and a non-conductive plate 25' 15 are employed, as in the design described before.

The lower ends of the fusible elements are electrically connected by means of a ring 18' which again is held tight by means 20 of threaded shell 27'. A washer 28' and a bolt 30' is employed for holding the parts together.

It will be seen that in this construction, the manufacture of the article is greatly 25 cheapened since it requires considerably less time to place the fusible elements in the device. In this way, the assembling operations are greatly simplified.

Figure 4 illustrates another form of my 30 device, in which the fusible elements 15'' are made in one piece with the ring-shaped disc 18''.

The body member 10'' consists of a hollow, substantially cylindrical portion, adapted 35 to support within a filament carrier 33' upon which again reposes a conductive member 19'', a perforable sheet 24'' and a non-conductive member 25''.

Again, a washer 28'' is employed and all 40 the parts are held together by means of a bolt 30''. The fusible elements in this case are insulated by means of a powder or dry sand indicated at 37, which is filling the place between the bottom portion of the device and the filament carrier 33'.

Contact with the outer shell 27'' is made in the same manner as described in the formerly described figures.

In each construction, the main feature of 50 employing a pierceable element is clearly seen. In use, the plug is inserted into the socket and pin 21 is then placed into one of the apertures provided in the insulated plate 25, 25' or 25'' respectively.

The sheet 24' or 24'' is then pierced by the pin, thereby permitting the pin to engage the thread of the openings in the conductive member 19, 19' or 19''. The pin is screwed 60 tight against the broadened portion of the fusible element so as to make perfect contact.

In this way, contact is made between the nut of the central bolt through the conductive member 19, the pin 21 and one fusible element and the outer threaded shell 27.

When one of the fuses burns out, another

fuse may be used in the aforementioned manner.

It is evident that by removing pin 21 from the aperture of the burned out fuse, the hole pierced into the sheet 24 remains thereby 70 indicating that that fusible element has been used.

It may be desired in some cases that the fuse be employed in circuits of higher amperage, in which case two or more pins may 75 be simultaneously inserted in various apertures provided in the plates, in which way, the fuse is capable of carrying a higher current.

While I have shown a specific form of my 80 device, be it understood that improvements and alterations in the design may be made without departing from the broad scope of my invention, for which I claim:

1. A multiple fuse comprising a dielectric body, dielectric fuse receiving means arranged within said body, a plurality of fusible elements associated with said fuse receiving means for electrically uniting one end of all elements, a conductive member disposed above said fuse receiving means and provided with means for facilitating making individual connection with the other ends of said elements, and means disposed above said conductive member and adapted to be broken before contact is made between said conductive member and said other ends of an element, and serving for indicating which of said elements has been used. 85

2. A multiple fuse, comprising a dielectric body, dielectric fuse receiving means within said body, a plurality of fusible elements conductively connected together at one of their ends, said fuse receiving means separating the other ends of said elements, a conductive member disposed above and electrically separated from said other ends of said elements, means for effecting conductive contact between said conductive member and the separated end of one element, a perforable sheet disposed above said conductive member and adapted to be pierced before permitting the making of contact between said conductive member and one of the separated element ends. 100

3. A multiple fuse, comprising a dielectric body, dielectric fuse element receiving means arranged within said body, a plurality of electrically separated fuse elements carried by said receiving means and electrically joined at one of their ends, the free end of each element provided with an enlargement, a conductive member disposed above the enlarged ends of the said elements and insulated from the latter and provided with means for receiving a contact making member, a perforable sheet arranged above said conductive member, and adapted to be pierced by said contact making member, and a dielectric covering member arranged over 110 115 120 125 130

- said sheet and adapted to allow the insertion of said contact making member.
4. A multiple fuse, comprising a dielectric body, dielectric fusible element receiving means arranged within said body, and provided with a plurality of cavities, a plurality of fusible elements carried by said receiving means and having one of their ends enlarged, said enlarged ends adapted to engage said cavities, the other ends of said elements adapted to be interconnected with each other, a perforated conductive member, disposed above said fusible element receiving means, the perforations of said conductive member arranged over the said cavities and provided with a thread, a perforable solid sheet secured above said conductive member, an insulating disc provided with perforations holding said sheet in place, the perforations of said insulating disc registering with said cavities of said receiving means,
- a threaded pin adapted to be inserted through the perforations of said disc, pierce said sheet, engage the threaded perforations of said conductive member and engage and make contact with said enlarged ends of said fusible elements.
5. The combination with a multiple fuse, including a plurality of fusible elements interconnected at one end and means for making individual electric connection at the other end of said elements, of a used fuse indicating means comprising a breakable member disposed over the individual ends of said elements and adapted to be punctured before electric contact may be made with the individual ends of said elements.

Signed at New York in the county of New York and State of New York this 21st day of April A. D. 1924.

HENNING NOTHDURFT.
